(57) **CLAIM**

The ornamental design for a weight rack attachment, as shown and described.

DESCRIPTION

FIG. 1 is a top, front, right perspective view of a weight rack attachment showing my new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; and, FIG. 8 is a bottom, front, left perspective view thereof. The broken lines immediately adjacent to the shaded area define the bounds of the claimed design and form no part thereof. The broken lines depicting the remainder of the weight rack attachment show features that form no part of the claimed design. The zig-zag lines and the bracket shown on the center of the weight rack attachment indicate indeterminate length and form no part of the claimed design.
